UNITED STATES PATENT OFFICE.

EUGENE F. OSBORNE, OF ST. PAUL, MINNESOTA.

STEAM-HEATING APPARATUS FOR RAILROAD ROUND-HOUSES.

SPECIFICATION forming part of Letters Patent No. 288,818, dated November 20, 1883.

Application filed March 31, 1883. (No model.)

To all whom it may concern:

Be it known that I, EUGENE F. OSBORNE, of St. Paul, in the county of Ramsey and State of Minnesota, have invented certain new and useful Improvements in Steam-Heating Apparatus for Railroad Round-Houses and Similar Situations; and I do hereby declare that the following is a full, clear, and exact description thereof, reference being had to the accompanying drawings, and to the letters of reference marked thereon, which form a part of this specification.

This invention is applicable to extended systems of steam-heating, or for a number of buildings having a common source of supply; but for the purpose of a more ready description and understanding of said invention, it is herein illustrated in a system adapted more particularly for engine-houses and similar situations, wherein some of its advantages are very important.

Heretofore in steam apparatus for heating round-houses or other buildings in which it is difficult or impossible to obtain any considerable vertical distance between the main steam-pipe and the return-pipe, and in which there is a large amount of heating-surface divided up into small sections and spread out over a wide area, there has been great difficulty in obtaining a proper simultaneous and satisfactory circulation of steam through all or a number of the coils composing the heating-surface, for the reason that the steam, usually taking the shortest circuit, would pass through some one coil of the system and into the main return-pipe. Upon opening the valves of another coil, therefore, the steam would enter said coil both from the supply and return pipes into both ends of the coil. This would prevent the escape of the air, which would consequently accumulate in the middle of the coil and prevent any proper circulation of steam through the said coil. Besides, owing to the slight vertical distance between the main return-pipe and the coil, the current of steam passing into the return end of the coil would often be sufficient to carry the water of condensation with it into the coil, which would produce hammering in the pipes, and consequent injury to the apparatus. Another diffi-

culty heretofore encountered is that as each coil usually connects directly with the main steam-supply pipe, and as the steam-pipe has a pitch or declines usually in the direction of the current of steam, if the coils on the extreme far end are shut off, the main steam-pipe will contain a quantity of water, and will hammer, and if exposed to a sufficiently low temperature will freeze.

It is an object of this invention to provide, in a heating apparatus having a small vertical distance between its feed and return pipes, a construction such that any one coil or heating apparatus connected therewith, or any section, group, or number of coils or heaters, may be turned on or off without regard to any other coil or section or group of coils, such that the steam-pipe will always be full of steam, whether one or all the coils are turned on or off, and such that the main return-pipes can be located in the immediate vicinity of, and either above, below, or at the side of, the main steam-supply pipe. Advantages of this last feature (of location) are, first, to prevent freezing of the return-pipe, (which is effected by reason of its proximity to the steam-pipe,) and, second, to lessen the excavation required to give place to the apparatus. It is a further object to provide a construction of the apparatus, such that each and every coil will circulate perfectly with minimum steam-pressure, and will, with its connections, be exempt from liability to freezing temperature.

To these and other ends that will appear the invention consists in the matters herein-after described and claimed.

Referring to the drawings, Figure 1 is a plan view of an engine round-house interior, showing ten pits arranged in groups of five each. Fig. 2 is an elevation of the supply and return mains, showing the traps in connection therewith. Fig. 3 is a perspective view of the heating apparatus for a single pit, showing its connections with the trap, and also the connections of the trap with the supply and return mains, together with fragments of the connecting return-pipes leading from the other heaters of the same group. Figs. 4, 5, and 6 are details of modifications.

A represents the circular wall of a round-

house, B the tracks for the engines, and P P the pits. S is the main steam-supply pipe, which runs around the building near the outer wall thereof, and R is the main return-pipe 5 for carrying the water of condensation back to the boiler. T is a trap connected with the pipes S and R by pipes S' and R', respectively. The several coils or heating devices located in the pits P are, as here shown, composed of vertical supply and return headers H and H' and pipes h h, and they are connected with the trap by means of supply-pipes S², S³, and S⁴, and by the return-pipes R² and R³. The apparatus comprises a main circuit and local circuits. 10 The main circuit includes the boiler, (not here shown,) the main steam-supply pipe S, suitably connected with the boiler, the return-pipe R, the traps T, and the pipes S' and R', connecting the several traps with the pipes S and R. The pipe S is constructed with several high and low points, marked, respectively, s and s', arranged, preferably, with the high points immediately over the low points, as 15 illustrated in Fig. 3 and in full lines of Fig. 2; but the high points may be located midway between the low points, as indicated at s' by the aid of the dotted lines in Fig. 2. At each low point the pipe S' is taken off the pipe S, preferably by a downwardly-directed outlet 20 from the latter, so as to drain the steam-supply pipe into the trap. Said trap is represented as an ordinary automatic continuous-discharge trap, and, when the return-pipe R is present, connects, as already stated, with 25 said pipe by the pipe R'. Said return-pipe may lead to any convenient point; but it will usually discharge into a tank arranged similarly to the tank marked F in Letters Patent No. 212,320, granted to me February 18, 1879, 30 whence the condense-water is returned to the boiler.

For the reason that round-houses are usually divided into sections of from four to eight stalls each, and for the purpose of simplifying the 35 apparatus and obtaining the most perfect circulation, the pit-heaters of a section or group of stalls are connected with the trap through single supply-pipes S² and S³ and a return-pipe, R², with which pipes S³ and R² the individual heaters are respectively connected 40 through the supply and return branches S⁴ and R³, as best seen in Fig. 3. There are therefore as many low points in the main S as there are traps, and there is a trap for each 45 group or section of stalls or pits, though, of course, so far as concerns the construction of the main S and the connections of the traps therewith, each individual heater or coil can be separately connected with a trap and the 50 number of traps increased to equal the number of such coils. When the heating-coils are connected in groups with the traps, as shown in the drawings, said traps are located in suitable pits, each placed preferably opposite the 55 middle of the group of stalls to which it belongs, and set at such a depth that the lower-

most pipes, h, of the coils and the ends of the branch return R³ adjacent to the coils are above the high-water line of the trap T. The pipe S³ declines both ways suitably from its 60 connection with the pipe S², and the individual returns R³ also decline toward the pipe R². Said pipe R³ is located below the low-water line in the trap T, so that each of the individual returns R³ is sealed with a water seal, which, 65 however, will not normally rise to the coil. Each individual supply and return is provided with a valve, V² V³, and valves V and V' are also provided in the pipes S² and R², for use when occasion requires. When steam is cut 70 off the coil, by closing the valves V² and V³, water would back up into the return branch R³, and, if exposed to a freezing temperature, as is often the case, said pipe would freeze and burst. To prevent this the pipe E is introduced and provided with a valve, e, which is 75 opened when the coil is cut off. By this means a circulation is maintained through the pipes S², S³, S⁴, E, R³, and R², and through the trap T, and freezing is avoided. This circulation is intended to be constantly maintained 80 in cold weather when the adjacent coil is shut off. The pipes last enumerated form with the trap and heater what I call a "local circuit." A valve or cock, V⁴, may be provided on the 85 side of the valve V' toward or beyond the returns R³, by which, when required, the water within the heaters and their returns may be drawn off. It will be observed that the returns R³ connect by short vertical pipes r with 90 the pipes R². This construction and the position of the mains S and R, as shown, render it unnecessary to excavate deeply, except for the trap and the return R², which latter may run in any direction and be of any length or 95 size. The return-pipe R may be provided at one or more points with an automatic float air-valve, or with a hand-valve, as a means of liberating air that may accumulate therein. 100 It is manifest that the steam-supply branch S', connected as described, serves a double purpose—namely, as a drain to the steam-supply main S and as a steam-supply pipe for the local circuit. The trap T acts also in a double capacity—to wit, as a connecting-link in the 105 main circuit when the local circuit is disused, and also as seal-tank and trap for the local circuit when the latter is in operation. 110 The essential features of operation will be effected if the pipe S² is made a prolongation 115 of the horizontal part of pipe S', or is directly connected with the main supply-pipe S at any point, as indicated in Figs. 4 and 5. The construction shown in Fig. 3 is, however, preferable. The feature of a balanced pressure between 120 the supply and return pipes S² R², with the tank-trap T, and that of a circulation by means of the pipe E, are subjects of the Patent No. 212,320, above referred to. Manifestly a pressure-reducing valve may be introduced in the 125 branch supply-pipe S' and a pressure carried on the local circuit less than that in the sup-

ply-main; but in the use of such a valve it is necessary to provide that it shall in all cases give passage to the water of condensation formed in the pipe S. Of course the pressure in the local circuit cannot be less than sufficient to dispose of the water of condensation through the trap. A special construction of a valve designed for this purpose may form the subject of a separate patent. It is evident that the deflections of the main steam-supply pipe, made for the purpose of obtaining the alternating high and low points, also serve to allow "give and take" in the expansion and contraction of said pipe resulting from changes of temperature. While the high and low points in the main steam-supply pipes are desirable, a proper (bottom) connection of the pipes S' with a perfectly-level supply-main will measurably serve to drain the latter, and I am not restricted to a main having such high and low points, except in those claims in which this feature is specified. The last-mentioned modification is shown in Fig. 6.

I claim as my invention—

- 25 1. Broadly, the combination, in a steam-heating apparatus, of a main steam-supply pipe, a series of local heating-circuits deriving their supply from said main, a series of traps connected at different points with said main in such manner as to drain the main at the several points of connection therewith, and connections for delivering the water of condensation from the heating-circuits to the traps, substantially as described.
- 35 2. In a system of steam-heating, the combination of a main supply-pipe, a series of traps connected with said main, so as to drain the same at their points of connection, a series of heaters or of groups of heaters, supply-pipes giving communication from the supply-main to the heaters or groups, return-pipes giving communication from the heaters to the traps, and valves located between the traps and heaters for cutting off the heaters, substantially as described.
- 45 3. In a system of steam-heating, the combination of a steam-supply main, a series of traps connected with said main at different points thereof in such manner as to drain the main at

the several points of their connection therewith, 50 a series of groups of heating devices, pipes S³, severally in communication with the individual heating devices of a group and with the supply-main, and return-pipes R², severally in communication with the several heating devices of a group and with a trap of the series, 55 substantially as described.

4. In the system of steam-heating, the combination, with the steam-supply main, with a trap, and with two or more heaters, of a pipe, 60 S³, in communication with the supply-main and with each of the heaters, a return-pipe, R², in communication with the trap and with each of the heaters, valves V and V', cutting off all the heaters, and valves V² and V³, cutting off each of the heaters, substantially as described.

5. In a steam-heating system, a supply-main having a series of alternating high and low points, and a series of traps connected 70 with the low points of said main, heaters in connection with the main, and return-pipes connecting the heaters with the traps, substantially as described.

6. In a system of steam-heating, the combination of a steam-supply main having alternating high and low points, a return-main for the water of condensation, and a series of traps connected with the several low points of the supply-main, and also connected with the 80 return-main, substantially as described.

7. In a system of steam-heating, the combination of a supply-main having alternating high and low points, a return-main, a trap connected with the return-main and with a 85 low point of the supply-main, a heater or group of heaters, and connections whereby the heater or group of heaters takes its supply from and returns its water of condensation to the trap, substantially as described.

In testimony that I claim the foregoing as my invention I affix my signature in presence of two witnesses.

EUGENE F. OSBORNE.
